IRONER

Luther Ringer, Union Springs, N. Y., assignor to
Easy Washing Machine Corporation, Syracuse,
N. Y., a corporation of Delaware

Application January 3, 1930, Serial No. 418,256

3 Claims. (Cl. 68—9)

This invention relates to a new and improved ironer and is particularly directed to a new and improved magnetic means for controlling the clutch for the ironing shoe.

8 The main object of my invention is to provide an ironer having a magnetic means for controlling the operation of the ironing shoe, which magnetic means is simple in design, positive in action and inherently free from any liability to 10 become out of order.

Other objects and advantages relate to the size, shape and arrangement of parts all as will more fully appear from the following description taken in connection with the accompanying 15 drawings in which:

Figure 1 is a top plan view of my improved ironer.

Figure 2 is a section on line 2—2 of Figure 3.

Figure 3 is a section on line 3—3 of Figure 2.

Figure 4 is a section on line 4—4 of Figure 1.

Figure 5 is a section on line 5—5 of Figure 3.

Figure 6 is a section on line 6—6 of Figure 3.

Figure 7 is a section on line 7—7 of Figure 6.

Figure 8 is a section on line 8—8 of Figure 6.

Figure 9 is a section on line 9—9 of Figure 1.

Although my invention is adapted to be used with various types of ironers, I have here shown it in combination with a particular type of ironer.

The ironer shoe support herein described is 20 similar to an improved ironer shoe support disclosed and claimed by me in a co-pending application for Ironer, filed October 9, 1929, Serial No. 398,386, and the particular means for operating the clutch for the ironer roll here described is 25 similar to a new and improved means disclosed and claimed by me in a co-pending application for Ironer filed November 29, 1929, Serial No. 410,484.

The ironer here described comprises a gear 30 casing 1 having a laterally extending boss 2 and a parallel laterally extending boss 3. A supporting tube 4 has one end positioned in boss 2 and has the other end secured in and supported by a saddle member 5.

45 A tubular shaft 6 is rotatably mounted in tube 4 and extends outwardly beyond saddle 5. On the outer end of tubular shaft 6 is pivotally mounted a yoke 7. Between the opposite sides of yoke 7 a member 8 is secured to shaft 6 as by a pin 9. In the outer end of member 8 is slidably mounted a shaft 10.

In the lower end of shaft 10 is secured a transverse pin 11. A spiral spring 12 encircles shaft 10 and has one end abutting against member 8 and the other end abutting against a washer 13

secured to the upper end of shaft 10 as by a nut 14.

On the lower end of yoke 7 is pivotally mounted on a pivot pin 15 a dog 16 having at its upper end a hook portion 17 adapted to engage transverse pin 11.

In the upper end of yoke 7 is pivotally mounted as by a pivot pin 18 a bell crank 19. In the upper end of bell crank 19 is secured a shaft 20 having a ball 21 on its upper end.

Adjacent the upper end of yoke 7 is secured 65 an ironer shoe 22 having an internally positioned resistance heating element 23. Shoe 22 is pivotally mounted on pin 18.

A shaft 24 has its lower end in engagement with dog 16 and passes thence upwardly through 70 a guide 25 secured in yoke 7 and thence through an aperture 26 in the upper end of yoke 7. A spiral spring 27 encircles shaft 24 with its upper end positioned in an aperture not shown in shaft 24 and with its lower end abutting against guide 75 25 to normally urge shaft 24 upwardly to move dog 16 about its pivot 15 to bring hook 17 into engagement with pin 11.

One arm 28 of bell crank 19 is in engagement with the upper end of shaft 24 so that when bell 80 crank 19 is moved about its pivot 18 in one direction shaft 24 will be forced downwardly to move dog 16 about its pivot 15 to carry hook 17 out of engagement with pin 11.

A depending lug 29 on the lower end of bell 85 crank 19 is adapted to engage the upper end of yoke 7 to limit the movement of bell crank 19 about its pivot in the opposite direction.

With dog 16 in engagement with pin 11, yoke 7 will be locked to member 8 so that any movement transmitted to shaft 6 will, through member 8, be transmitted to yoke 7.

For the purpose of holding shoe 22 in the raised position when it is out of contact with the ironer roll hereinafter to be described, I provide a leaf 95 spring 30 having its upper end secured to shoe 22 as by bolt 31 and having its lower end in engagement with the lower end of yoke 7.

In the boss 3 is secured an outwardly extending tubular shaft 32. A ironer roll 33 is journaled 100 on shaft 32 by means of a bearing 34 adjacent its inner end and with a similar bearing not shown adjacent its outer end.

An internal gear 35 is secured adjacent the inner end of roll 33 as by screws 36. In the outer face of gear casing 1 is positioned an internally extending tubular boss 37 in which is secured a bearing 38 for one end of a shaft 39. The other end of shaft 39 is journaled in a bearing 40 provided in the opposite side of gear casing 1.

For the purpose of operating tubular shaft 6 to effect operation of ironer shoe 22, I provide on shaft 39 a worm gear 40 rotatably mounted on shaft 39. Worm gear 40 is in mesh with a worm 51 carried on the armature shaft of a motor 42 which, for convenience, is mounted in a vertical position on gear casing 1.

On shaft 39 is rotatably mounted a cam member 42 which is positioned in the open end of jaw arm 43. The other end of jaw arm 43 is secured to the inner end of shaft 6, as by a pin 44. On the side of cam member 42 which faces worm gear 40 is pivotally mounted a clutch dog 45 as by a pivot pin 46.

On the hub 47 of worm gear 40 is secured, as by a pin 48, a clutch member 49 provided on its periphery with spaced recesses 50 adapted to receive a finger 51 carried on dog 45.

A spring 52 has one end secured to cam member 42, as by a pin 53, and has its other end secured to dog 45 to normally move dog 45 about its pivot to bring finger 51 into registration with a recess 50.

When dog 45 on cam 42 is in registration with clutch member 49, the cam 42 will be operatively connected to the worm gear 40 so that the rotation of such gear 40 will cause the rotation of cam 42.

The rotation of cam 42 will cause an oscillating movement of jaw arm 43, which oscillating movement will be transmitted to shaft 6.

For the purpose of holding dog 45 out of registration with clutch member 49 so that cam member 42 will be at rest, I provide an arm 54 having a U-shaped upper end provided with round apertures through which the inner end of a shaft 55 extends so that member 54 is free to rotate on shaft 55.

Shaft 55 is journaled in a bearing 56 in gear casing 1. The outer end of shaft 55 is secured as by a pin 57 to an operating handle 58.

The lower end of member 54 is U-shaped and is adapted to be moved into and out of the path of movement of dog 45. When member 54 is in the path of movement of dog 45, such dog 45 will be held in spaced relation to clutch member 49 with finger 51 out of registration with apertures 50.

A hook-shaped member 59 has its lower end positioned between the opposed faces of the upper end of member 54, shaft 55 extending through an out of round aperture in member 59 so that member 59 and shaft 55 are locked against relative rotary movement.

Member 59 has on its lower end a lug 59' adapted to contact with one side of the upper end of member 54 so that when shaft 55 is rotated to rotate member 59, lug 59' will bear against the upper end of member 54 to cause the latter to be moved about its pivot and out of the path of movement of dog 45.

As perhaps may best be seen from Figure 5, a spiral spring 60 has one end secured to casing 1 and has the other end secured to the upper end of member 59 to normally cause member 59 to be moved about its pivot, such movement being limited by the contacting of the upper end of member 59 with casing 1.

When member 59 is in this position the lug 59' is in a position to permit member 54 to be moved above its pivot and into the path of movement of dog 45.

A spiral spring 54' has one end secured to casing 1 and has the other end secured to the upper end of member 54 to normally urge the latter

about its pivot and into the path of movement of dog 45.

The movement of member 54 in this direction is limited by a stop 54'' formed in casing 1.

It will be understood that the pivotal movement of shaft 55 may be effected manually by means of a handle 58. Member 54 functions as an armature for magnet 61 secured to gear casing 1 so that when such magnet 61 is energized member 54 will be caused to move about its pivot towards magnet 61 and out of the path of movement of dog 45.

I have here shown diagrammatically a wiring diagram and a switch 62 for magnet 61, no source of potential being indicated, but it will be understood that any desired type of switch may be utilized, although I prefer to use a foot operated switch so that the magnet 61 may be energized by a foot, leaving the hands of the operator free.

In order to insure that the dog 45 will be moved a sufficient distance about its pivot 46 when it contacts with member 54 so that 51 will be moved in spaced relation to clutch member 49, I employ an arrangement of parts which may best be seen from Figures 6, 7 and 8.

A plate 63 is pivotally mounted on pivot pin 46 and conforms in shape and position approximately to dog 45. One end of plate 63 is bent as shown at A on Figure 8 to a position in spaced relation to the end of dog 45.

A spiral spring 64 is interposed between the end of plate 63 and the end of dog 45. The upper edge of plate 63 is also bent outwardly as shown at b on Figure 8 above the upper end of dog 45 to limit the upward movement of dog 45 with reference to plate 63 under the action of spring 64.

The spring 52 heretofore described is secured to the end of plate 63 in opposed relation to spring 64. When the member 54 is in the path of movement of plate 63 and the same is brought into contact therewith, the spring 64 will be compressed and the dog 45 will be raised to carry finger 51 out of registration with clutch member 49. The spring 64 will then expand to carry dog 45 further about its pivot 46 to position the finger 51 in spaced relation to the clutch member 49 so that there will be no possibility of the two contacting while the clutch member 49 continues its rotation.

The movement of plate 63 and dog 45 takes place when the end of plate 63 to which the spring 52 is attached contacts with the member 54. If the opposite end of plate 63 contacts with member 54, the same movement of parts will take place due to the fact that such end of plate 63 is held against further movement which will cause plate 63 to be moved about its pivot to compress spring 64 and move dog 45 about its pivot to carry finger 51 out of registration with clutch member 49, after which spring 64 will expand to move dog 45 further about its pivot 46 to carry finger 51 to a position in spaced relation to clutch member 49.

For the purpose of imparting rotary movement to the roll 33, I provide a gear 65 rotatably mounted on shaft 39. One face of gear 65 is provided with circumferentially spaced clutch teeth 66 adapted to engage opposed clutch teeth 67 provided on one face of gear 40.

As described in my before-mentioned application Serial No. 410,484, shaft 39 is adapted to be moved intermittently axially by means of a key 68 in shaft 39 which bears against a cam surface 69 on the inner end of bearing 38.

A further description of the operation just described is not essential to a description and ex-

planation of my invention which is primarily directed to the operation of the clutch which controls the ironing shoe.

Adjacent boss 3 and in casing 1 is journaled a shaft 70 having on its inner end a gear 71 in mesh with gear 65.

The outer end of shaft 70 carries a gear 72 in mesh with internal gear 35. With gear 65 in clutching engagement with gear 40, the continuing 10 rotary motion of gear 40 will be communicated to gear 65 and will thence through gear 71, shaft 70, gear 72 and gears 35 be communicated to roll 33.

Operation

15 When it is desired to operate the machine, the heating unit 23 in shoe 22 is connected to a source of potential by means of a lead 73. The switch-controlled motor 42 is then connected, and rotary motion will then be conveyed in the manner and 20 through the gearing above described to the gear 40 and thence to the roll 33.

25 The clutch dog 45, not being operatively connected to the clutch member 49, the cam 42 will not rotate. The cam 42 is eccentrically mounted on shaft 39 so that the rotation of the same when effected will cause an oscillating movement of member 43 as the high side of cam 42 alternately contacts with the opposed jaw ends of member 43.

30 With the parts in the positions shown in Figure 2, the high side of the cam 42 is in contact with the lower jaw of member 43 so that the inner end of member 43 is in the fully depressed position. In this position, the shaft 6 will have been 35 rotated in an anti-clock-wise direction to the fullest extent and this movement will have carried the shoe 22 into pressure engagement with the roll 33.

If desired, the parts may be left in this position 40 and the articles to be ironed introduced between the shoe 22 and the roll 33. The roll 33 rotating the article will be carried downwardly between the shoe 22 and the roll 33. If it is desired to move the shoe 22 away from roll 33 to permit of 45 more careful arrangement of the articles to be ironed before the actual ironing operation, the member 54 by the use of handle 58 or preferably switch 62 will be moved out of the path of movement of dog 45 so that finger 51 will engage clutch member 49 to cause the rotation of cam 42.

The handle 58 or the switch 62 having been 50 immediately released, the member 54 will return into the path of movement of the dog 45 so that the dog 45 will be stopped and moved out of engagement with clutch member 49 as soon as cam 42 has completed a half revolution. When this 55 has taken place, the high side of cam 42 will be in contact with the upper jaw of member 43 so that the inner end of member 43 will have been raised to the highest position with the result that the shaft 6 will have been rotated to the fullest extent in a clock-wise direction to carry the shoe 22 out of engagement with the roll 33.

When it is again desired to have the shoe 22 60 come into ironing relation with the roll 33, the handle 58 or the switch 62 is again manipulated to move member 54 out of the path of movement of dog 45 to permit the latter to engage the clutch member 49 to cause the rotation of cam 42. This intermittent operation of shoe 22 may be continued as desired.

It sometimes happens that the motor 42 is suddenly and unexpectedly cut off from the source of potential as, for example, by the blowing of a fuse and if this takes place when the shoe is in 75

pressure contact with the roll 33 any article which might be between them would probably be scorched or burned due to the fact that the heating element 23 and the shoe 22 will retain their heat for some time, and inasmuch as the roll 33 will have ceased to rotate, the article will be held between it and the shoe 22.

In order to provide a means whereby the shoe 22 may be moved away from the roll 33 irrespective of the operating mechanism just described, I have provided the shoe support heretofore described so that in case of emergency, the operator may move the handle 20 to pivot bell crank 19 and cause dog 16 to be moved about its pivot to carry hook 17 out of engagement with pin 11 and break the connection between yoke 7 and member 8 so that yoke 7 carrying shoe 22 may be moved outwardly from the roll 33.

In order to limit this outward movement of 95 yoke 7, I provide on yoke 7 a laterally extending pin 74 adapted to contact with a lug 75 on member 5.

As disclosed in my above referred to application Serial No. 398,386, a means is provided whereby the yoke 7 will automatically be again 100 locked to the member 8 when the machine resumes its operation, but inasmuch as an understanding of such means is not essential to the understanding of the invention disclosed in this application, I will not describe it in detail.

105 It will be understood that my invention is adapted to be used with various types of ironing machines and it will also be understood that the exact arrangement of parts here disclosed may be varied to a considerable degree without departing 110 from the spirit of my invention for although I have shown and described a specific structure and form and arrangement of parts as an exemplification of an embodiment of my invention, I do not desire to restrict myself to the exact size, 115 shape or relation of parts as various changes may be made within the scope of the appended claims.

I claim:

1. In an ironing machine, a roll, means for rotating the roll, an ironing shoe movable into and 120 out of engagement with the roll, means for moving the shoe, motor means, means connecting said motor means in driving relation with said shoe moving means including a clutch member normally urged into driving relation with said 125 motor means, a shaft, an arm pivotally mounted upon said shaft and normally engaging said clutch member to hold said member out of driving relation with said motor means, an electro-magnet for moving the said arm out of engagement 130 with said clutch member when said electro-magnet is energized, a switch controlling the energizing of said magnet, and a crank arm rigidly mounted on said shaft movable into contact with said first arm and adapted for manual actuation 135 to move the first arm out of engagement with said clutch member independently of said electro-magnet.

2. In an ironing machine, a roll, means for rotating the roll, an ironing shoe movable into and 140 out of engagement with the roll, means for moving the shoe, motor means, means connecting said motor means in driving relation with said shoe moving means including a clutch member normally urged into driving relation with said 145 motor means, a shaft, an arm pivotally mounted upon said shaft and normally engaging said clutch member to hold said member out of driving relation with said motor means, an electro-magnet for moving the said arm out of engage- 150

ment with said clutch member when said electro-magnet is energized, a switch controlling the energizing of said magnet, a crank arm mounted on said shaft rigid therewith, movable into contact with said first arm and adapted for manual actuation to move the first arm out of engagement with said clutch member independently of said electro-magnet, means for limiting the rocking movement of said crank arm, and a spring tensioned to move said crank arm into contact with said limiting means.

3. In an ironing machine, a rotatable roll and a movable shoe, means for moving the shoe toward

and away from the roll comprising a pair of clutch elements, a shaft, an arm rotatably mounted on said shaft and normally maintained in the path of movement of one of said clutch elements to hold the clutch elements in disengaged relationship, electro-magnetic means for moving said arm about the shaft to withdraw it from engagement with said clutch element, and alternate manually operated means for withdrawing said arm from engagement with said clutch element comprising a member rigid with said shaft and movable into contact with said arm.
